UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

LADDER FOR CARS.

1,062,191.

Specification of Letters Patent.

Patented May 20, 1913.

Application filed November 9, 1911. Serial No. 659,325.

To all whom it may concern:

Be it known that I, HARRY H. SCHROYER, a citizen of the United States, and a resident of the city of Chicago, in the county of Cook and State of Illinois, have invented certain new and useful Improvements in Ladders for Cars; and I do hereby declare that the following is a full, clear, and exact description of the same, reference being had 10 to the accompanying drawings, and to the numbers of reference marked thereon, which form a part of this specification.

Accidents have frequently happened owing to the failure of the grab irons or the 15 ladders or some part thereof, attached to the car end, which, giving away under the weight of the operator, permits him to fall beneath the car. This has frequently been occasioned from the manner of construction 20 of the ladder at the side or end of the car, which usually is constructed of separate bars or rods bent to the proper form and secured in place by means of lag screws passing through the ends thereof and into the wood 25 of the car side or frame.

The object of this invention is to afford a ladder in which the individual rounds are secured upon suitable stiles and the ladder as a whole attached to the car side or end 30 by means of bolts, which act to rigidly engage the same in place.

It is also an object of the invention to afford an exceedingly cheap, and simple construction, adapted to be knocked down for 35 shipment, and permitting quick assembling and installation.

It is further an object of the invention to afford in connection with a ladder such as described, a reinforcement for that portion 40 of the stiles extending below the car bottom to support the lower round or step and as a whole to afford an exceedingly strong, durable and safe construction.

The invention in its preferred form, is 45 hereinafter more fully illustrated and described.

In the drawings: Figure 1 is a fragmentary end elevation of a car equipped with a ladder embodying my invention, showing 50 the ladder applied on one side and one end thereof at the corner. Fig. 2 is an enlarged fragmentary transverse section of the installation illustrated in Fig. 1, showing the attaching bolts in elevation. Fig. 3 is an 55 end elevation of one of the rounds or steps

before insertion into the stile. Fig. 4 is a side elevation broken away, of one of the stiles, with the flanges cut away between the rounds. Fig. 5 is an enlarged fragmentary front elevation of the lower portion of 60 the ladder. Fig. 6 is a rear elevation thereof. Fig. 7 is a bottom plan view of one of the rounds, showing the stiles in section, and illustrating the method of securing the rounds in the stiles. Fig. 8 is an enlarged 65 detail similar to Fig. 7, and showing the round and one stile broken away. Fig. 9 is an enlarged fragmentary rear elevation showing the upper end of one of the stiles and the end of the round attached thereto. 70

As shown in the drawings: 1, indicates the car end; 2, the corner frame post within the car; 3, the outer covering or car side and end; and 4, the longitudinal block or reinforcing strip secured on the inner side 75 of the car opposite the point of attachment of the ladder thereto.

5, 6, and 7 indicate the stiles for the ladder, in this instance shown as three in number, inasmuch as the ladder is illustrated 80 attached to the car side and end at one corner thereof to afford a side ladder and an end ladder. Of course, where attached to the side or to the end only, but two stiles 85 are required.

The stiles, as shown, each comprise a deep, narrow rolled channel having a web 8, and lateral flanges 9, which extend substantially parallel for a distance corresponding with, or slightly greater than the thickness of the 90 round and thence diverge bracingly, as shown in Figs. 2, 7, and 8, and are provided at the upper and the lower end thereof with outwardly directed foot flanges 10, which are apertured to receive the bolts 11, whereby the stiles are attached in place. The foot flanges for the side and end stiles are, of course, turned outwardly in the same plane while the foot flanges 12, for the center or corner stile 7, are turned at an 95 angle of 90 degrees with reference to each other to engage the corner of the car.

As shown, a bottom guard plate 13, is secured by spot welding or other suitable means, to the foot flanges of said stiles, 105 serving to rigidly tie the same together at the bottom and at the top and acting to sustain in part, the thrust occasioned by an operator when boarding a moving car.

Each of the tiles 5 and 6, as shown in 110

Figs. 2 and 4, is provided with an aperture through the inner side of the flange closely adjacent the web 8, said aperture, as shown in Fig. 4, being substantially rectangular except at the bottom where the boundary thereof is rounded. The corner stile, where the ladder is secured both on the end and side, as shown in Figs. 1 and 2, is provided with apertures through both flanges, those in each flange being arranged at the same height as the aperture in the adjacent side tile, said apertures being arranged, however, in the corner stile to break joints, as illustrated in Fig. 2, and as shown in dotted lines in Fig. 1. The rounds 14, also of pressed steel, are shown as tubular, and are rolled to afford a continuous top and sides with the edges of the strip from which the round is constructed, brought together or meeting on the under side thereof.

The ladder is assembled by inserting the ends of the rounds through the apertures in the sides of the stiles, and then inserting a suitable tool of any kind and flaring the ends of the round, as illustrated in Figs. 7, 8, and 9, thereby so enlarging the same as to preclude the withdrawal thereof from the stiles. As shown in Fig. 3, the end of the round is shaped to fit accurately in the complementary aperture therefor in the stile.

Of course, if it should be desired, the foot flanges may extend for the entire length of the stile. Ordinarily, however, this is neither necessary nor desirable, inasmuch as the stiles are exceedingly strong and rigid, being rolled of a sufficiently heavy gage of metal to serve the purpose. If the flanges of the stiles are cut away, as illustrated in Fig. 4, intermediate the foot flanges, at the upper and lower end thereof, a lighter structure is afforded and one that permits the operator to engage the stile with his hand as well as the round, should it ever be necessary.

Of course, it is to be understood that details of the construction may be varied. I therefore do not purpose limiting the patent to be granted on this application otherwise than necessitated by the prior art.

I claim as my invention:

1. A device of the class described embracing channeled stile members, integral legs extending therefrom at each end thereof, bearing feet on said legs and integral therewith adapted for attachment to a car, and a plurality of rungs connected into each of said channeled stile members.

2. In a device of the class described channeled stile members having apertures therein, a plurality of tubular rungs having a longitudinal slot on the under side thereof and the ends of said rungs extending into said apertures in the stiles and the corners thereof flanged over to rigidly engage the ends in said stiles.

3. In a device of the class described a ladder rung comprising a tubular member having a longitudinal slot on the underside thereof, said ladder rung flattened on the upper surface affording a step, and the ends of said rungs adjacent said longitudinal slot adapted to be flanged outwardly for attachment.

4. In a device of the class described channeled stile members having apertures in one wall thereof, tubular rung members having a longitudinal slot in the underside thereof and extending into the apertures and bearing against the opposite wall of said channeled members, and the lower end of said rungs within said channeled members adapted to be expanded to rigidly secure the rungs in said stile members.

5. In a device of the class described a tubular rung, the upper surface thereof flattened to afford a step, the lower surface rounded and having a longitudinal slot therein, and the ends of said member open adapting the same to be expanded for attachment.

In testimony whereof I have hereunto subscribed my name in the presence of two subscribing witnesses.

HARRY H. SCHROYER.
